UNITED STATES PATENT OFFICE

2,455,109

METHOD OF FABRICATING MERCHANTISE
HOLDERS AND DISPLAY DEVICES

Fredrick H. Bowers, Kalamazoo, Mich.

Application June 28, 1945, Serial No. 602,087

1 Claim. (Cl. 93—3)

1

This invention relates to improvements in merchandise holders and display devices, and to a method of fabricating the same, having for one of its objects, to provide a novel and comparatively inexpensively producable device for effectually holding and attractively and uniquely displaying merchandise containing packets.

Another object of the invention is to provide a device of the stated character, by means of which various articles of merchandise may be conveniently and efficiently retained in package form, protected from soilage and/or shop wear and, when desired, readily disengaged or removed for sale without damage to either the removed package or the holder thereof.

The invention also aims to provide a merchandise holder and display device so constructed that it and the merchandise containing packets supported thereby will occupy only a minimum of space, but nevertheless, will be possessed of all essential merchandising advantages and features, i. e., display appeal, security of product packaging, practical simplicity of product removal both from the holder and the packet, and manufacturing economies.

Another important feature of the invention resides in the advantageous and novel method of producing the device, whereby the holder and the merchandise receiving packets are produced from a single piece of stock material, are covered and packaged with the least possible number of operations and the least possible amount of materials, and are of simple, rugged and durable character.

The foregoing, as well as other objects, advantages and meritorious teachings of the invention, will be in part obvious and in part pointed out in the following detailed disclosure thereof, when taken in conjunction with the accompanying drawings; it being understood that the particular form of the invention presented herein is a precise and what is now considered to be the best mode of embodying its principles, but that modifications and changes may be made in specific embodiments without departing from its essential features.

In the drawings:

Figure 1 is a side elevation of one of the sheets of material employed to cover the opposite sides of the display device body, one corner thereof being turned to show the application of an adhesive to its reverse side.

Figure 2 is a side elevation of the body of the device.

Figure 3 is a longitudinal section through the 55 The assembly thus made, including the open-

2

device body taken on the line 3—3 of Figure 2, looking in the direction in which the arrows point.

Figure 4 is a longitudinal section through the body of the device which has one of its sides covered with sheet material, such as shown in Figure 1, and wherein merchandise has been placed in the retaining openings provided to the device body.

Figure 5 is a similar section having the opposite side of the device body covered by a single sheet of material, such as shown in Figure 1, whereby the remaining ends of the merchandise receiving openings in the device body are closed and the merchandise received in such openings 15 is thereby securely packaged.

Figure 6 is a side elevation of the completed merchandising device.

Figure 7 is a longitudinal section taken on the line 7—7 of Figure 6, looking in the direction in 20 which the arrows point, and

Figure 8 is a transverse section taken on the line 8—8 of Figure 6, looking in the direction in which the arrows point.

Having more particular reference to the drawings, the numeral 1 generally designates a preferably rectangularly shaped body made of form sustaining material, such as cardboard, fibre board, composition, etc., having a plurality of definitely spaced groups of correspondingly 25 shaped and sized openings 2 formed therein appropriately throughout its area. Over one face side of the body 1 a piece of similarly shaped and sized sheet material 3, such as paper or other comparatively easily rupturable material is engaged and secured thereto by an applied adhesive, thus facing said side and also, closing the adjacent ends of the various groups of openings 2, as will be observed upon reference to Figure 4 of the drawings.

Articles such, for example, as the so-called 40 "flints" (bodies of pyrophoric material) used in pyrophoric pocket lighters, are placed into each of the openings 2, whereupon a second piece of sheet material 5, corresponding in shape, size and structure to the piece 3, is engaged over and 45 adjoined to the opposite and remaining side of the body 1, thus closing the remaining ends of its openings 2. Jointure of this second piece of sheet material 5 to the body 1 may, of course, be effected by applying a suitable adhesive thereto.

Because of the closing of the ends of the article receiving and retaining openings 2 in the body 1, it will be seen that an effective individual packing of the "flints" will be provided.

ing provided body 1 and the opposite side covering sheets 3 and 5, is now die cut through one side thereof to a depth or distance approximately mid-way of said body, as indicated at 6. Thereupon, the body is reversely positioned and then die cut through its opposite side, as at 7, to a point in proximity to the inner extremities of the first cuts 6. The second made die cuts 7 in the body 1, as shown in Figures 7 and 8, are laterally offset with relation to the first made cuts and, as will be noted, do not connect therewith. Consequently, the adjacent intermediate portions of the body 1 remain intact for a purpose which will be presently apparent.

The die cuts 6 and 7 are made in the body 1 in a manner to completely inclose or circumscribe each of the individual groups of openings 2 formed therein (see Figure 6). Preferably, the die cuts are so relatively arranged and joined to each other as to present rectangularly shaped formations, though it is to be understood that such formations may be changed as conditions or preference may dictate, insolong as they are effected in a manner to completely surround or embrace therewithin all of the openings 2 of a particular or single group and that all such groups of openings 2 shall be so embraced.

It is to be understood that any desired number of groups of openings 2 may be formed in the device body 1 and that such number will, in the remain, be regulated by the character of their respective dispositions within the body and the overall size or area of said body.

The body 1 and its covering sheets 3 and 5, may be longitudinally perforated or formed with openings 8 along and adjacent one side thereof. In this manner, they may be permanently or temporarily connected by suitable binding devices (not shown) and thus retained in book or cumulated form. Moreover, the device bodies 1 and their covering sheets 3 and 5, plus articles of merchandise housed or packaged thereby, may be retained between the covers of suitable permanent or temporary binders.

In the use of a packaging device such as above described, when it is desired to remove a merchandise packet therefrom, pressure is applied to one side of one of the panel-like sections embraced by the hereinbefore described die cuts 6 and 7, thus rupturing or tearing the adjacent intermediate body portions between the inner ends of the die cuts 6 and 7 and permitting the particularly engaged panel-like section or packet to be freely removed therefrom. When a panel-like section or merchandise containing packet has been removed from the device body 1, the merchandise retained within the particular group of openings 2 formed therein may be readily removed from the pockets 2 of its particular body portion, by appropriately engaging a suitable implement with the packet adjacent one of the openings 2 and then thrusting such implement through the adjacent rupturable sheet material 3

or 5, into and through said pocket and through the adjacent portion or the remaining piece of rupturable material 3 or 5. The merchandise 4 will be thus ejected from its opening 2.

At this point, attention is particularly directed to the fact that because of the relatively lateral offsetting of the oppositely disposed die cuts 6 and 7 in the body 1 and the covering sheets 3 and 5, as well shown in Figure 6 of the drawings, the jointure of the die cut circumscribed portions of the device with adjacent portions thereof will be materially weakened—weakened to such an extent that they may be readily broken away upon the application of comparatively slight pressure thereto. Irrespective of such weakening of the jointure between the die cut inscribed portions of the device body and the remainder thereof, however, the panel-like packets will be effectually retained within the body 1 until deliberately removed therefrom in the manner hereinbefore described.

Whereas, I have herein described, with some degree of particularity, my improved merchandise holder and display device as receiving "flints," it will be fully understood and appreciated that various articles of merchandise may be received within the grouped openings 2 of the body 1; also, that the shape and size of the various groups of openings 2 may be varied or changed without departing from the spirit or scope of the invention.

I claim:

A method for producing a merchandise holder and display device, which consists of forming a plurality of groups of openings in a sheet-like form sustaining body; covering one side of the body with a sheet of material whereby to permit retention of articles in said openings; covering the opposite side of the body with a second sheet of material to close the remaining sides of the openings in said body, and then cutting through each of said sheets of material in continuous lines circumscribing each of said groups of openings in said body and extending said continuous circumscribing cuts partially through the body in relatively different and offset planes.

FREDRICK H. BOWERS.
